ABSTRACT: The presence of *Pseudomonas* in biological media containing other micro-organisms is determined by adding to the media from 100 to about 800 parts per million of a compound of the formula:

wherein R is halogen and R₁ is hydrogen or chloro.

The medium is then maintained at 20° to 40° C. for an incubation period of 12 hours to 14 days. A particularly preferred compound useful in this method is 2,4,4'-trichloro-2'-hydroxydiphenyl ether.

METHOD FOR THE DETERMINATION OF
PSEUDOMONAS IN BIOLOGICAL MEDIA
BACKGROUND OF THE INVENTION

Finding an effective means for the isolation and detection of bacteria belonging to the genus *Pseudomonas* has been long sought by those working in the biological and medical arts. A simple and rapid means of isolating and identifying these bacteria is highly desirable since they are responsible for numerous pathogenic disturbances in humans, animals and plants.

The charred skin of burn patients is particularly susceptible to *Pseudomonas* with resultant serious infections and sometimes death. *Pseudomonas* is often involved in urinary, intestinal and conjunctival infections.

Pseudomonas are responsible for numerous plant diseases, such as lettuce leaf rot; and for the deterioration of various materials such as food, paint, latex, plastics, asphaltic material and various liquids, creams and lotions employed for cosmetic and pharmaceutical purposes.

Up to the time of the present invention, there has been no rapid method available for isolating and differentiating these *Pseudomonas* from other micro-organisms present in clinical body fluids or on other substrates.

The usual procedure for isolating and differentiating *Pseudomonads* from other micro-organisms involves plating the samples onto a Gram-differentiating media, having a trained bacteriologist pick presumptive colonies from the media, and then subjecting the organisms to various biochemical tests. Under ideal conditions and in the hands of highly trained personnel, a positive diagnosis of *Pseudomonas* required 3 to 4 days. The direct quantitative enumeration of *Pseudomonas* in a sample containing a mixture of micro-organisms has been an almost impossible task.

This invention provides a simple and efficient method of isolating and detecting *Pseudomonas* in varied biological media containing *Pseudomonas* and any other micro-organisms.

According to this invention, (a) a nutrient medium is provided which includes from about 100 to 800 parts per million of a compound of the formula

wherein R is halogen and R₁ is hydrogen or chloro, (b) said medium is inoculated with a sample containing unknown micro-organisms, (c) said medium is maintained at a temperature of about 20° to about 40° C. for an incubation period of 12 hours to 14 days, and (d) said medium is observed for the presence of *Pseudomonas*.

Additionally, methods are provided for the simultaneous isolation and differentiation of *Pseudomonas* strains producing fluorescent pigments, pyocyanin pigments or hydrogen sulfide.

A particularly preferred compound of the above formula for use in the method of this invention is 2,4,4'-trichloro-2'-hydroxydiphenyl ether. It is stable to steam sterilization and does not interfere with other usual ingredients added to form a complete biological medium, for example, metal salts, buffers, blood, proteins, liquids, indicators and carbohydrates. The reagent is not pH sensitive, and generally any medium having a pH within the range of 3.0 to 9.0 is suitable for the practice of this invention.

While an addition of 100 parts per million of the 2,4,4'-trichloro-2'-hydroxydiphenyl ether is generally sufficient to differentiate between all of the micro-organisms and *Pseudomonads*, it is generally preferred to add between about 300 and about 500 parts per million to further insure that all other colonies except *Pseudomonads* have been eliminated. Up to

about 800 parts per million may be added, but greater amounts are wasteful and approach the point where the growth of strains of *Pseudomonads* will be inhibited.

The following examples describing certain representative embodiments of this invention will serve to further illustrate the nature of the invention. It is to be understood that the examples are merely illustrative and intended to enable those skilled in the art to practice the invention in all of the embodiments flowing therefrom and do not in any way limit the scope of the invention defined in the claims.

EXAMPLE I

Various commercial biological media containing agar were dissolved in distilled water and sterilized for 10 to 15 minutes at 15 pounds pressure (121° C.). The media were cooled to 50° C. and varying amounts of 2,4,4'-trichloro-2'-hydroxydiphenyl ether added from a filter sterilized solution of the compound in methyl cellosolve. The media containing the various indicated levels of 2,4,4'-trichloro-2'-hydroxydiphenyl ether were then inoculated with pure cultures of indicated micro-organisms and solidified in petri dishes. After a suitable period of incubation (1-10 days) the plates were inspected for visible signs of growth.

As indicated in the following table I, all of the wide representative spectrum of micro-organisms which included bacteria, fungi and yeast which were tested failed to grow when 2,4,4'-trichloro-2'-hydroxydiphenyl ether was present in an amount of 100 parts per million or more. The *Pseudomonas*, however, flourished in all media which contained as high as 300 parts per million of 2,4,4'-trichloro-2'-hydroxydiphenyl ether.

¹ In parts by million of 2,4,4'-trichloro-2'-hydroxydiphenyl ether.

The following examples further demonstrate the effectiveness of 2,4,4'-trichloro-2'-hydroxydiphenyl ether in differentiating *Pseudomonas* from other micro-organisms. Typical media which may be prepared beforehand and have incorporated therein a suitable amount of 2,4,4'-trichloro-2'-hydroxydiphenyl ether for use in the practice of this invention are illustrated.

EXAMPLE II

A general purpose medium suitable for the isolation and differentiation of *Pseudomonas* species is prepared as follows:

Peptone	20 g.
Magnesium chloride	1.4 g.
Potassium sulfate	10.0 g.
Agar	15.0 g.
2,4,4'-Trichloro-2'-Hydroxydiphenyl Ether	0.25 g.

To rehydrate the medium, 46.65 g. of the above formulation is dissolved in distilled water and sterilized by autoclaving for 15 minutes at 15 pounds pressure (121° C.). For an especially clear medium 10 grams of methyl cellosolve can be added to 1,000 ml. of the hot suspension prior to autoclaving. Alternatively, the methyl cellosolve can be added to the dry ingredients at the time of manufacture in which case the 2,4,4'-trichloro-2'-hydroxydiphenyl ether is first dissolved in the

methyl cellosolve and this uniformly blended into the other portion of the formulation. As a second alternative, the formulation without the 2,4,4'-trichloro-2'-hydroxydiphenyl ether can be compounded, rehydrated, sterilized, and the 2,4,4'-trichloro-2'-hydroxydiphenyl ether added from a filter sterilized solution in methyl cellosolve.

As indicated in the following table II, various strains of *Pseudomonas* grew on the above medium after 24 hours incubation at 37° C. while other bacteria normally growing in the above medium without 2,4,4'-trichloro-2'-hydroxydiphenyl ether failed to grow.

TABLE II

Micro-organisms	Growth After 24 Hours at 37° C.
<i>Pseudomonas aeruginosa</i>	Growth
<i>Pseudomonas fluorescens</i>	Growth
<i>Pseudomonas pyocyanea</i>	Growth
<i>Staphylococcus aureus</i>	No Growth
<i>Escherichia coli</i>	No Growth
<i>Proteus vulgaris</i>	No Growth
<i>Bacillus subtilis</i>	No Growth
<i>Salmonella typhosa</i>	No Growth

EXAMPLE III

A medium particularly well suited for the simultaneous isolation and differentiation of *Pseudomonas* strains producing fluorescein pigments is prepared by incorporating 2,4,4'-trichloro-2'-hydroxydiphenyl ether into the following ingredients by the methods described in example II:

Proteose Peptone No. 3*	20 g.
Maltose	10 g.
Dipotassium phosphate	1.5 g.
Magnesium sulfate	0.3 g.
2,4,4'-trichloro-2'-hydroxydiphenyl ether	0.25 g.
Agar	15 g.

*Manufactured by Difco Laboratories

50 To rehydrate the medium, 47.05 g. of the powder is dissolved in 1,000 ml. of water and sterilized by autoclaving. As in example II, methyl cellosolve is added at the time of manufacture, added later by the user prior to autoclaving or the base ingredients without 2,4,4'-trichloro-2'-hydroxydiphenyl ether prepared and the 2,4,4'-trichloro-2'-hydroxydiphenyl ether added from a filter sterilized methyl cellosolve solution after rehydration and autoclaving.

While the base medium without 2,4,4'-trichloro-2'-hydroxydiphenyl ether can differentiate fluorescin producing strains of *Pseudomonas* previously isolated from other bacteria, the addition of 2,4,4'-trichloro-2'-hydroxydiphenyl ether renders isolation and differentiation possible in one step. *Pseudomonas* strains producing fluorescin are visualized on the above medium as yellow colonies; the pigment also dissipates into the surrounding agar. The production of pyocyanin pigments associated with certain other strains of *Pseudomonas* is generally inhibited.

EXAMPLE IV

A medium particularly well suited for the simultaneous isolation and differentiation of *Pseudomonas* strains producing pyocyanin pigments is prepared by incorporating 2,4,4'-

trichloro-2'-hydroxydiphenyl ether into the following ingredients by the methods described in examples II and III.

Peptone	20 g.
DL-Alanine	2 g.
Sodium citrate	10 g.
Potassium sulfate	8.6 g.
Potassium chloride	1.4 g.
Magnesium sulfate	- g.
2,4,4'-trichloro-2'-hydroxydiphenyl ether	0.25 g.
Agar	15 g.

The medium is rehydrated by dissolving 58.65 grams of the medium in 1,000 ml. of distilled water and sterilizing by autoclaving. As in examples II and III methyl cellosolve can be added at the time of manufacture, added later by the user prior to autoclaving or the base ingredients without 2,4,4'-trichloro-2'-hydroxydiphenyl ether prepared and the 2,4,4'-trichloro-2'-hydroxydiphenyl ether added from a filter sterilized methyl cellosolve solution after rehydration and autoclaving.

Strains of *Pseudomonas* producing pyocyanin produce blue colonies; the pigment also diffuses into the surrounding agar. The production of fluorescin pigment is generally inhibited.

EXAMPLE V

A medium well suited to isolate and simultaneously differentiate *Pseudomonas* strains producing hydrogen sulfide is prepared by incorporating 2,4,4'-trichloro-2'-hydroxydiphenyl ether in the following formulation:

Peptone	15 g.
Proteose Peptone	5 g.
Ferric Ammonium Citrate	0.5 g.
Dipotassium phosphate	1 g.
Sodium thiosulfate	0.08 g.
Agar	15 g.
2,4,4'-Trichloro-2'-hydroxydiphenyl ether	0.25 g.

The medium is rehydrated by dissolving 58.65 grams of the medium in 1,000 ml. of distilled water and sterilizing by autoclaving. Alternatively the 2,4,4'-trichloro-2'-hydroxydiphenyl ether is added as described in examples II through IV.

Cultures of *Pseudomonas putrefaciens* are isolated as black colonies while other strains of *Pseudomonas* are grayish-tan.

Although the present invention has been described with preferred and specific embodiments, it is to be understood that modifications and variations may be resorted to, without departing from the spirit and scope of this invention, as those skilled in the art will readily understand. Such variations and modifications are considered to be within the purview and scope of the appended claims.

What is claimed is:

1. A method for the detection and isolation of *Pseudomonas* which comprises

a. providing a nutrient medium which includes from about 100 to about 800 parts per million of a compound of the formula

wherein R is halogen and R₁ is hydrogen or chloro,

b. inoculating said medium with a sample containing unknown micro-organisms,

c. maintaining said medium at a temperature of about 20° to about 40° C. for an incubation period of 12 hours to 14 days, and

d. observing said medium for the presence of *Pseudomonas*.

2. A method as claimed in claim 1 wherein from about 300 to about 500 parts per million of 2,4,4'-trichloro-2'-hydroxydiphenyl ether is present in said nutrient medium.

5 3. A method for the simultaneous isolation and differentiation of *Pseudomonas* strains producing fluorescin pigments which comprises

a. providing a nutrient medium comprising proteose peptone, maltose, dipotassium phosphate, magnesium sulfate, agar and from about 100 to about 800 parts per million of a compound of the formula

20 wherein R is halogen and R₁ is hydrogen or chloro,

b. inoculating said medium with a sample containing unknown micro-organisms,

c. maintaining said medium at a temperature of about 20° to about 40° C. for an incubation period for 12 hours to 14 days, and

d. observing said medium for the presence of said *Pseudomonas* strains as yellow colonies.

4. A method as claimed in claim 3 in which from about 300 to about 500 parts per million of 2,4,4'-trichloro-2'-hydroxydiphenyl ether is present in said nutrient medium.

5. A method for the simultaneous isolation and differentiation of *Pseudomonas* strains producing pyocyanin pigments which comprises

35 a. providing a nutrient medium comprising peptone, DL-alanine, sodium citrate, potassium sulfate, agar and from about 100 to about 800 parts per million of a compound of the formula

wherein R is halogen and R₁ is hydrogen or chloro,

b. inoculating said medium with a sample containing unknown micro-organisms,

c. maintaining said medium at a temperature of about 20° to about 40° C. for an incubation period of 12 hours to 14 days, and

d. observing said medium for the presence of said *Pseudomonas* strains as blue colonies.

6. A method as claimed in claim 5 in which from about 300 to about 500 parts per million of 2,4,4'-trichloro-2'-hydroxydiphenyl ether is present in said nutrient medium.

7. A method for the simultaneous isolation and differentiation of *Pseudomonas* strains producing hydrogen sulfide which comprises

60 a. providing a nutrient medium comprising peptone, proteose peptone, ferric ammonium citrate, dipotassium phosphate, sodium thiosulfate, agar and from about 100 to about 800 parts per million of a compound of the formula

75 wherein R is halogen and R₁ is hydrogen or chloro,

- b. inoculating said medium with a sample containing unknown microorganisms,
- c. maintaining said medium at a temperature of about 20° to about 40° C. for an incubation period of 12 hours to 14 days, and
- d. observing said medium for the presence of said Pseu-

- domonas strains as black colonies.
- 8. A method as claimed in claim 7 in which from about 300 to about 500 parts per million of 2,4,4'-trichloro-2'-hydroxydiphenyl ether is present in said nutrient medium.
